JOSEPH FRANK CULVERWELL, OF WASHINGTON, DISTRICT OF COLUMBIA, ASSIGNOR
TO ELLIOTT-FISHER COMPANY, OF HARRISBURG, PENNSYLVANIA, A CORPORATION
OF DELAWARE.

RESTORING MECHANISM FOR ADDING-MACHINES.

1,141,946.

Specification of Letters Patent. Patented June 3, 1915.

Application filed February 24, 1910. Serial No. 845,896.

To all whom it may concern:

Be it known that I, JOSEPH FRANK CULVERWELL, a citizen of the United States of America, residing at Washington, in the District of Columbia, have invented certain new and useful Improvements in Restoring Mechanism for Adding-Machines, of which the following is a specification.

My present invention relates to restoring mechanism for adding machines, and more particularly to mechanism for simultaneously restoring the carrying mechanism of a plurality of computing devices or registers constituting parts of a combined writing-adding machine adapted for multi-column addition.

By way of premise, it may be stated that in certain writing-adding machines now on the market, particularly what is known to commerce as the Elliott-Fisher machine, a typewriter is equipped with a plurality of computing devices or registers each including a series of denominational members or number wheels, carrying mechanism which automatically carries or transfers the amount accumulated in a given denomination to the denomination of next higher order, and restoring mechanism which is operated to restore or reset the carrying mechanism after the accumulation of each number.

The operation of the restoring mechanism is ordinarily effected automatically by the retraction of the typewriter carriage, a cam movable with the latter being brought successively into coöperative relation with the restoring slides of the several registers and thus accomplishing the restoring of the carrying mechanisms of all of the registers as the typewriter carriage is brought back to begin the next line of writing. This method of restoring, while effective and in practical use at this time, obviously burdens the retraction of the carriage and this burden naturally increases with the number of registers, fifteen or twenty of which are commonly employed on a single machine.

As distinguished from the method above described, the object of my invention is to provide a motor-operated, carriage-con-

trolled restoring mechanism for the entire complement of registers, whereby the typewriter carriage will be relieved of the burden of restoring the carrying mechanisms of the several registers, but will, nevertheless, by its position, determine the time at which the restoring mechanism shall operate under the impulse of its own driving motor.

A subordinate object of the invention is to so arrange the restoring mechanism that the latter will effectively coact with any register or registers, regardless of the particular column positions they may occupy within the limits of the machine.

Other objects subordinate to those enumerated will appear as the description of the illustrated embodiment of the invention is developed.

In the accompanying drawings Figure 1 is a sectional elevation of an Elliott-Fisher writing-adding machine equipped in accordance with my invention with parts non-essential to the present disclosure omitted. Fig. 2 is a plan view of the same with the registers indicated in dotted lines. Fig. 3 is a diagrammatic view showing the restoring motor or solenoid, a portion of the typewriter carriage and the mechanism whereby the operation of the motor is controlled. Fig. 4 is a detail perspective view of the controlling mechanism. Fig. 5 is a rear elevation of a portion of the frame with the registers and the universal restoring mechanism mounted thereon, and Fig. 6 is a detail view of one of the rocker supporting brackets. Fig. 7 is a side elevation of the controlling mechanism, showing the parts in the positions they assume when the carriage, after causing the closing of the circuit, effects automatically the opening thereof.

Each part is indicated by its appropriate reference character throughout the views.

1 indicates the flat platen, 2 the main machine frame and 3 the carriage of an Elliott-Fisher machine. The carriage supports writing mechanism 4 operated by keys 5 which also control the letter space movement of the carriage in a manner well understood in the art. In rear of the car-

riage 3 the frame 2 supports what is known as a register bar 6 adjustably supporting a number of computing devices or registers 7 operated by a master wheel 8 movable with the carriage 3 and rotated upon the depression of the keys 5 by intermediate operating connections 9.

For a more complete disclosure of the adding equipment reference is made to Patents Nos. 825,469 to Laganke and Smith, 825,494 to John A. Smith, 829,791 to Laganke and Smith and to the co-pending application of Laganke and Smith No. 308,279.

15 Each of the registers 7 includes, as usual, what is known as the restoring slide 10 which, when moved back, effects the resetting of the carrying mechanism. So far as the register is concerned, the present invention contemplates no exchange except that the restoring slides 10 instead, of having their front ends extended beyond the front of the registers for coaction with a cam on the carriage, are each provided with 20 a dependent pin 11 dropped sufficiently below the bottom of the register to coact with the universal restoring bar 12 of a restoring yoke 13 carried by brackets 14 secured to the register supporting bar 6 as 25 by screws or other suitable securing devices 15. The restoring yoke 13 includes, besides the bar 12, a pair of side members 16 of angular or bell-crank form pivoted at their angles to the brackets 14.

30 35 Extended between the ends of the member 16 remote from the bar 12 is a second transverse bar 17 having connection with a restoring motor 18 adapted when operated to swing the yoke 13 for the purpose of 40 causing the bar 12 by coaction with the pins 11 to operate the slides 10 of the registers in order to restore the carrying mechanism thereof. In its broader aspects it is immaterial what character of motor is employed 45 for this purpose. In the present disclosure the motor 18 is in the form of a solenoid, the core or armature 19 of which is formed at its upper end with a hook 20 engaging the bar 17 and provided at its lower end 50 with a switch member or circuit controlling device 21. Encircling the core 20 between the switch member 21 and the body portion of the solenoid is a spring 22 which compels the retraction of the armature or core 55 19 when the solenoid is deenergized.

60 65 23—23 indicate the terminals of the solenoid winding which are equipped with binding posts 24 for the attachment of the line wires *a* and *b* leading to a battery or other suitable source of electrical energy *c*. The motor 18 is mounted on a bracket 25 screwed or otherwise secured to the main frame of the machine, as shown in Fig. 1. It will now be seen that if this circuit, including the battery and solenoid, is closed, the latter will

be energized and the armature 19 thereof will rise against the resistance of the spring 22 thereby swinging the restoring yoke 13 and simultaneously restoring the carrying mechanisms of all the registers. As soon, 70 however, as the armature 19 reaches the limit of its upward movement, the switch member 21 will engage and span the interval between the terminals 23 thus short-circuiting the current and deenergizing the 75 solenoid, the spring 22 immediately retracting the parts to normal position.

80 Located in the motor circuit is a circuit closing device 26 which may be and preferably is mounted on one of the carriage stops 27 which are ordinarily adjustably mounted on the frame of the machine and are set to arrest the carriage at any desired limit of movement. The circuit closing device 26 comprises two terminals 26^a and 26^b suitably insulated from the stop 27 and arranged to be spanned by one end of a spring-retracted plunger 26^c likewise mounted on but insulated from the stop 27. This circuit closing device is adapted to be manually operated since the operator may at any time press the plunger 26^c into contact with the terminals 26^a and 26^b thus closing the circuit through the solenoid and energizing the same to operate the universal restoring 90 mechanism of the registers. Obviously this manual control of the motor circuit is entirely independent of the carriage and may be effected regardless of the particular location of the carriage on the frame. It is 100 intended, however, to provide for both the manual and automatic control of the restoring mechanism so that, while the latter may be rendered active at any time, regardless of the position of the carriage, it will 105 also be brought into action automatically when the carriage reaches a given position, preferably when the carriage is retracted to begin a new line of writing.

To accomplish this automatic control the 110 arm or bracket 28 usually extended from the left hand end of the carriage to engage the carriage stop 27 is provided with a pivoted plunger-operating member 29 disposed in line with the plunger 26^c of the 115 circuit closing device 26. Thus when the carriage of the typewriter is retracted the member 29 will contact with the plunger 26 urging the latter between the terminals 26^a and 26^b and closing the circuit. Obviously, 120 the particular point in the retractile movement of the carriage at which the operation of the restoring mechanism shall take place may be regulated by the adjustment of the stop 27 upon the frame in the usual manner. 125

The mechanism as thus far described is entirely effective because the circuit will be closed upon the retraction of the carriage thus starting the restoring motor the armature of which, upon the complete actuation 130

thereof, will automatically shunt the circuit around the motor, thus permitting the retraction of the armature, the reenergizing of the motor and continued repetition of the 5 operation of the motor as long as the circuit controlling device 26 remains closed. An operation of this character may be desirable when a large number of registers are employed because if the resistance opposed by 10 the registers approximates the capacity of the motor the first operation of the motor may not completely effect the restoring of the carrying mechanism of all of the registers and in that event, one or more repetitions of the motor operation to absolutely insure complete restoring of all the registers may be desirable. Unless provision is 15 made to the contrary, the plunger 26^a will remain between the terminals 26^a and 26^b 20 and retain the circuit in closed condition until the carriage again moves to the right thus withdrawing the plunger-operating device 29 from the plunger 26^a and permitting the retraction of the latter under the influence 25 of its retracting spring 26^d. Consequently as long as the carriage remains in its fully retracted position, the circuit controlling device 26 remains closed and the restoring motor will repeatedly operate by 30 reason of the alternate energizing and de-energizing of the latter in consequence of the action of the circuit controlling device 21. When, however, the resistance of the registers is well within the capacity of the 35 motor a single operation of the latter would be entirely effective to operate the several restoring mechanisms with certainty and precision. Under such conditions it would not be economical to keep the circuit closed 40 through the battery, or other source of electrical energy, for a greater period than would be sufficient to cause a single reciprocation of the motor armature. On the contrary, it would be sufficient if the carriage, 45 upon its retraction, should first effect the closing of the circuit and subsequently open the circuit after an interval sufficient for the proper energizing of the motor and restoring of the registers. 50 To this end the plunger-operating member 29 is provided with a cam finger 30 designed upon the retraction of the carriage to coact with a pin 31 mounted on a relatively fixed part; as for instance on the stop 27. 55 The member 29 is so proportioned that as the carriage nears the end of its retractile movement said member 29 will engage and operate the plunger 26^a to close the circuit and after the lapse of a suitable interval for 60 the operation of the motor will be swung out of interfering relation with the plunger 26^a by the coaction of the cam finger 30 and the pin 31. This will allow the retraction of the 65 plunger and the opening of the circuit. (See Fig. 7.) When the carriage again moves to

the right the member 29 will swing back to normal position for a repetition of the described operation when the carriage is again retracted.

When it is not desired that the carriage shall automatically effect the opening as well as the closing of the circuit during its retractile movement, it is merely necessary to remove the pin 31, in which event the plunger will not be released for retraction until the carriage again moves to the right, after having operated the plunger to close the circuit. In either event, that is to say, whether the retraction of the carriage merely closes the circuit or both closes and opens the circuit, the switch member 21 is useful because even if it is not desired that the motor shall operate repeatedly, careful relative adjustment of the finger 30 and pin 31 is rendered unnecessary by the presence of the member 21 which, upon the rising of the armature 19, will automatically shunt the circuit and before the motor can again operate, the member 29 will have been withdrawn from the plunger 26^a and the circuit opened. In addition to the manual and automatic control of the motor I provide the yoke 13 with a handle 32 by means of which it may be manually operated.

It will be seen that the invention here disclosed comprehends a universal restoring mechanism for a plurality of computing devices or registers which latter are variable as to relative position and that such universal restoring mechanism is arranged for both manual and automatic control. It will also be noted that the universal restoring mechanism is controlled by the carriage, but operated from an independent source of power and that the mechanism whereby the carriage control of the restoring mechanism is made possible, is variable to determine the point in the movement of the carriage at which the restoring mechanism shall operate.

It is thought that from the foregoing, the construction and operation of the illustrated embodiment of my invention will be fully comprehended, but I expressly reserve the right to effect such changes, variations and modifications of the illustrated structure as may come fairly within the scope of the protection prayed.

What I claim is:

1. The combination with a plurality of relatively adjustable computing devices each including carrying means, of restoring mechanism common to the carrying means of said computing devices and operative to restore the same simultaneously.

2. The combination with a plurality of computing devices relatively adjustable to different column positions and each including carrying mechanism, restoring means therefor, of operating mechanism common

- to the restoring means of the several computing devices and arranged to operate the same simultaneously.
3. The combination with a plurality of computing devices relatively adjustable laterally and each including carrying means, of restoring mechanism common to the carrying means of the several computing devices and operative in the various adjusted positions of the latter to restore said carrying means simultaneously.
4. The combination with a plurality of computing devices relatively adjustable laterally and each having carrying mechanism and restoring means therefor, of a universal operating member in constant coöperative relation with the restoring means of the several computing devices.
5. The combination with a plurality of computing devices relatively adjustable in a lateral direction and each including carrying devices and restoring means therefor, of a universal bar disposed transversely of the registers and movable to operate the several restoring means.
6. In an adding machine, the combination with two primary elements, to-wit a frame and a carriage, of register operating means mounted on one of said primary elements, a plurality of registers mounted on the other of said primary elements and including carrying mechanism, and universal restoring means mounted on the primary element which supports the registers and operative to restore the carrying mechanisms of the several registers.
7. In an adding machine, the combination with a frame, of a carriage movable thereon, register operating mechanism mounted on the carriage, a plurality of registers mounted on the frame and each including carrying mechanism, and restoring mechanism also mounted on the carrying mechanism of the frame and common to the several registers.
8. In an adding machine, the combination with a plurality of registers relatively adjustable laterally and each including carrying means, of actuating mechanism for the registers, a frame and carriage supporting the registers and their operating mechanism, and restoring mechanism common to the carrying means of the several registers and operative independently of the carriage.
9. In an adding machine, the combination with two primary elements, to-wit a frame and a carriage, of a plurality of separate registers mounted on one of said elements and each including carrying devices, actuating means mounted on the other element, and mechanism mounted on the register supporting element and operative to simultaneously restore the carrying devices of the several registers.
10. The combination with a plurality of registers each including carrying means of universal restoring mechanism manually operative to simultaneously restore the carrying means of the several registers.
11. The combination with a plurality of separate registers each including carrying means and relatively adjustable in a lateral direction, of restoring means for the carrying means of each register, and a swinging yoke coacting with the restoring means of the several registers.
12. The combination with a series of registers relatively adjustable laterally and each having carrying mechanism and restoring means therefor, of a universal yoke extending across the series of registers and coacting with the restoring means thereof.
13. The combination with a register support, of a plurality of registers adjustable along the support and each including carrying mechanism, and restoring mechanism including a member extending in the general direction of the register support, and coacting with the carrying mechanisms in the various adjusted positions of the registers.
14. The combination with a plurality of separate registers relatively adjustable laterally and each including carrying means, of motor-operated restoring mechanism common to the carrying means of said registers.
15. The combination with a plurality of separate registers each including carrying means and relatively adjustable laterally, of motor-operated universal restoring mechanism operative in the various adjusted positions of the registers to simultaneously restore the carrying means thereof.
16. The combination with a computing mechanism including a plurality of independent registers each including carrying means, of motor-operated restoring mechanism common to the carrying means of said registers, and automatic means controlling the operation of the motor.
17. The combination with an adding mechanism including a plurality of independent registers each having carrying devices, of restoring mechanism common to the carrying devices of the several registers, a motor for operating said restoring mechanism, and means for stopping and starting the motor.
18. The combination with adding mechanism including a plurality of independent registers each having carrying devices, of motor-operated restoring means common to the carrying devices of the several registers, and a movable carriage controlling the operation of said restoring means.
19. An adding mechanism including a laterally adjustable register having carrying devices, restoring means for said carrying devices, a carriage coöperatively related to the restoring means in a given position of said carriage, and means adjustable ind-

pendently of the register to vary the position of the carriage in which such coöperative relation will be established.

20. The combination with a plurality of 5 separate distinct registers each having carrying devices, of restoring mechanism common to the carrying devices of said registers, a traveling carriage coöperatively related to the restoring mechanism in a given 10 position of said carriage, and variable means for determining that position of the carriage in which the coöperative relation shall be established.

21. The combination with a plurality of 15 separate distinct registers each having carrying devices, of universal restoring mechanism operative to simultaneously restore the carrying devices of several registers, and a traveling carriage coöperatively related to 20 the restoring mechanism.

22. The combination with a plurality of 25 separate distinct registers each having carrying devices, of motor-operated restoring mechanism common to the carrying devices of the several registers and operative to simultaneously restore said devices, and a traveling carriage coöperatively related to 30 said restoring mechanism.

23. The combination with a register having 35 carrying means, of restoring mechanism for said means, an operating motor for the restoring mechanism, a traveling carriage, and means whereby the movement of the carriage in a single direction will effect the starting and stopping of the motor.

24. The combination with a plurality of 40 separate distinct registers each having carrying means, of restoring mechanism for said means, an electrical motor for operating the restoring mechanism, a source of electrical energy, a motor circuit including said motor and source of energy, and automatic means controlling said circuit.

25. The combination with a plurality of 45 registers relatively adjustable laterally and each including carrying devices, of restoring mechanism common to the carrying devices of said registers, an electrical motor for operating the restoring mechanism, a source of electrical energy, a motor circuit, and circuit controlling means including a traveling carriage.

26. The combination with a register having 50 carrying means, of restoring mechanism for said means, an electrical motor for operating the restoring mechanism, a source of electrical energy, a motor circuit, and circuit controlling means including a traveling carriage arranged by its movement in one direction to both close and open the circuit to effect the starting and stopping of the motor.

27. The combination with a plurality of 55 distinct registers each having carrying devices and universal restoring mechanism

for the carrying devices of the several registers, of an electrical motor for the restoring mechanism, a motor circuit, a source of electrical energy, and a circuit controlling device operated by the motor.

28. The combination with a register having 60 carrying devices and restoring mechanism therefor, of a motor for the restoring mechanism, a traveling carriage, and a motor controlling device operative by the 65 traveling carriage and adjustable in the direction of the carriage travel.

29. The combination with a register having 70 carrying devices and restoring mechanism therefor, of a motor for the restoring mechanism, a traveling carriage, an adjustable stop for said carriage, and motor controlling means including a carriage-operated device mounted on and adjustable with the carriage stop.

30. The combination with a plurality of 75 separate and distinct computing devices each including carrying mechanism displaced from normal position during the operation of the device, of operating mechanism for 80 the computing devices, and restoring mechanism independent of the operating mechanism and operative to simultaneously restore the carrying mechanisms of the several computing devices to normal position.

31. The combination with a plurality of 85 registers relatively adjustable laterally and including carrying mechanism, of motor operated, universal restoring mechanism operative in the various relative positions of the registers to restore the carrying mechanism thereof.

32. The combination with a plurality of 90 registers relatively adjustable laterally, of motor operated universal restoring mechanism operative to restore the carrying mechanism of the several registers simultaneously.

33. The combination with adding mechanism including a plurality of separate and 95 distinct registers, each including carrying mechanism, of motor operated restoring means common to the carrying mechanisms of the several registers, and a movable carriage controlling the operation of said registers.

34. In an adding machine, the combination with two primary elements to wit, a frame and a carriage having relative movement, of a plurality of registers and operating means therefor, the denominational relation of the registers and their operating means being controlled by the relative movement of the frame and carriage, and restoring means operative to simultaneously restore the carrying mechanisms of the several registers.

35. In a machine of the character described the combination with a plurality of 100 registers adapted to be variably spaced
